ELECTRIC SWITCH DEVICE

Claude M. Hines, Verona, Pa., assignor to Westinghouse Air Brake Company, a corporation of Pennsylvania

Application March 29, 1949, Serial No. 84,036

3 Claims. (Cl. 200—146)

1

This invention relates to electric switches and more particularly to a switch device adapted to minimize arcing due to circuit interruption.

Arcing at the contact elements (hereinafter referred to simply as contacts) of a circuit-interrupter or switch device incidental to circuit interruption has long been a problem, particularly in high voltage and high current circuit-interrupters. In the smaller switch devices the problem exists to a lesser extent. In all cases, the service life of an interrupter or switch depends largely, if not entirely, upon the amount of pitting or burning of the separable contacts resulting from arcing.

It is an object of this invention to provide an improved electric switch device characterized by an arrangement for minimizing arcing at the separable contacts thereof upon circuit interruption and thus prolonging the service life of the device.

It is also an object of this invention to provide an improved electric switch device that operates automatically to introduce resistance into the circuit to reduce the current in the circuit at the instant of circuit interruption.

Other objects and advantages of the invention will appear in the following more detailed description thereof, taken in connection with the accompanying drawings in which Fig. 1 is a side view, partly in section, of an electrical switch device constructed in accordance with my invention and shown in its closed position; Fig. 2 is a fragmentary sectional view, taken along the line 2—2 of Fig. 1, and showing further details of construction; and Fig. 3 is a side view, partly in section, showing the switch device in its open position.

Referring to Fig. 1 of the drawings, the switch device comprises a rigid current-carrying arm 1, two flexible resilient contact arms 2 and 3, of suitable metal or metallic alloy, inherently biased toward each other as more fully explained hereinafter, and a rigid stop arm 4 of insulating material positioned between said flexible contact arms 2 and 3, all of the arms 1, 2, 3 and 4 being suitably mounted in a base 5 of suitable insulating material.

Interposed between arms 1 and 2 and having its opposite ends suitably electrically connected, as by soldering, to arms 1 and 2, respectively, is a variable resistance spring transducer 6 which automatically stretches responsively to downward movement of contact arm 2. It is a characteristic of the transducer 6 that a small amount of displacement or extension of the transducer re-

2

sults in a large increase of resistance of the transducer. The spring transducer 6 is so constructed that as it is expanded or stretched from its normal contracted position the turns of the spring progressively separate, thereby effecting a corresponding increase in the electrical resistance of the spring. The percentage change in resistance of the spring transducer 6 may be hundreds of times greater than the percentage change in length as it is expanded. Spring transducers of this type have been previously known and the transducer, in itself, is thus not my invention.

The ends of arms 1 and 3 mounted in the base 5 are provided with suitable terminals 7 and 8 to enable the arms 1 and 3 to be connected to a circuit (not shown) which is to be interrupted.

The free ends of the resilient contact arms 2 and 3 are provided with suitable contact discs 9 and 10 which engage firmly in the normal or closed position of the switch due to the inherent bias of the two arms in opposite directions. In view of the fact that flexible arms 2 and 3 are thus inherently biased, it follows that if arm 3 is moved downwardly, as by means to be described hereinafter, the arm 2 will also move downwardly, the contact discs 9 and 10 remaining engaged until the downward movement of these two arms is sufficient to permit arm 2 to engage the stop arm 4, at which time any further downward movement of arm 3 will cause the contact discs 9 and 10 to part from each other. It must be noted here that the inherent biasing force in arm 2 is sufficient to cause the spring transducer 6 to be expanded as the arm 2 flexes downwardly. If the force causing the downward movement of arm 3 is removed, the resilient nature and the inherent biasing forces of the two arms 2 and 3 will cause these arms to return to the position shown in Fig. 1 wherein contact discs 9 and 10 reengage.

Any suitable means may be provided for moving arm 3 downwardly to the circuit-open position shown in Fig. 3 and holding the arm in such position until it is desired to return it to its normal circuit-closing position. As shown, such means may comprise a lever mechanism mounted in the base 5 and including a yoke 11 of insulating material straddling the arm 3 and having a transverse cylindrical portion 12 which engages the contact arm 3. The free ends of the yoke 11 are provided with non-circular holes, shown as square holes in the drawing, to receive and interlock with a square section of a pin 13 which

extends transversely through a portion of the base 5. As will be seen in Fig. 2, pin 13 has cylindrical portions at opposite ends thereof to enable rotation thereof in the base 5 and is secured therein by a suitable means such as a cotter pin 19. A lever 14, having a square hole therein through which the square portion of pin 13 extends, is mounted between the free ends of the yoke 11 in such a manner that angular movement of the lever 14 will, through the medium of pin 13, be transmitted to and result in a corresponding angular movement of the yoke 11. It will thus be seen that as the lever 14 is shifted in a clockwise direction from the position in which it is shown in Fig. 1, yoke 11 shifts correspondingly in the same direction to effect downward flexing movement of the contact arm 3.

The end of lever 14 adjacent to pin 13 has two angularly related flats 15 and 16 with which cooperates a leaf spring 17 that is attached as by several screws 18 to the base 5 for the purpose of holding the lever 14 positively in either one of two different positions corresponding to the "circuit-closed" position and the "circuit-open" position respectively of the contact arms 2 and 3.

The switch device in its normal or closed position is as shown in Fig. 1. As previously explained, the two flexible arms 2 and 3 are biased towards each other and will thus be positioned in a substantially symmetrical relation to the stop arm 4 as shown in Fig. 1 with the contact discs 9 and 10 in engagement with each other. With the arm 2 in this position, the transducer or spring 6 will be held in its contracted position thereby, as explained previously, offering a minimum electrical resistance to a current flowing in a circuit from terminal 7 by way of arm 1, transducer 6, arm 2, contact disc 8, contact disc 10 and arm 3 to the terminal 8.

When the lever 14 is shifted in a clockwise direction from the rotation in which it is shown in Fig. 1, the yoke 11 moves correspondingly in a clockwise direction and the transverse portion 12 of said yoke 11 pulls the arm 3 downwardly. The downward movement of arm 3 and contact disc 10 permits the inherent biasing force of arm 2 to flex the arm 2 and contact disc 9 downwardly. The downward movement of arm 2 and contact disc 9 will automatically stretch or expand the spring transducer 6, thereby increasing the electrical resistance thereof in the circuit described in the previous paragraph and thus decreasing the current in the said circuit. As the clockwise movement of lever 14 causes further downward movement of arms 2 and 3, the electrical resistance of the spring transducer 6 increases correspondingly until the arm 2 engages the stop arm 4, at which time the current in the said circuit will have been reduced so greatly that the parting of the contact discs 9 and 10 (as will occur with further downward movement), will cause little or no arcing. If the lever 14 is moved in a clockwise direction past the line of juncture between flats 15 and 16, the spring 17 will snap lever 14 to its full "circuit-open" position and maintain it in that position, as shown in Fig. 3, by engagement with flat 16.

To restore the switch to its "circuit-closed" position it is necessary only to move the lever 14 in a counter-clockwise direction past the line of juncture between flats 15 and 16, whereupon spring 17 will snap the lever 14 to its "circuit-closed" position and maintain it thereon by en-

gagement with flat 15. The resilient nature and the inherent biasing forces of the arms 2 and 3 will thus be effective to return the said arms to their normal position symmetric with respect to arm 4 and cause the contact discs 9 and 10 to reengage.

Having now described the invention what I claim as new and desire to secure by Letters Patent is:

10. An electrical switch device comprising two flexible resilient contact members inherently biased in opposite directions into engagement with each other, means for flexing one of said contact members in opposition to the biasing force thereof whereby movement of the other of said contact members is effected correspondingly in response to the inherent biasing force thereof, a rigid stop member engageable by the other of said contact members upon a certain amount of movement in response to the inherent biasing force thereof, separation of said contact members being effected as the said one contact member is flexed in opposition to the inherent biasing force thereof beyond the point at which the said other contact member engages said stop member, and variable resistance means operatively responsive to the flexing movement of said other contact member in its traverse to the point of engagement with the stop member for effecting an increase of resistance in the circuit through said switch device immediately prior to disengagement of the contact members.
20. An electrical switch device comprising two flexible resilient contact members inherently biased in opposite directions into circuit closing contact with each other, a rigid stop member positioned between said contact members, means for flexing one of said contact members away from said stop member in opposition to the biasing force thereof, thereby causing movement of the other of said contact members toward the stop member to be effected in response to the inherent biasing force thereof, the ultimate extent of movement of said other contact member being so limited by engagement with said stop member as to effect separation of said contact members from each other as the said one contact member is flexed beyond the point at which said other contact member engages said stop member, a rigid current-carrying support member, and a variable resistance spring transducer connected between said rigid current-carrying support member and said other contact member effective to progressively increase the resistance in the circuit through said switch device as the said other contact member traverses from its normal circuit-closing contact position to engagement with said stop member.
30. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent
40. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent
50. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent
60. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent
70. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent
80. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent
90. An electrical switch device comprising a supporting base of insulating material, a pair of flexible resilient contact members each secured at one corresponding end in said base in spaced relation and being inherently biased in opposite directions to effect circuit-closing engagement of the free ends thereof, a stop member of insulating material interposed between said contact members, means supported by said base operative to engage and move one of said contact members in opposition to the inherent biasing force thereof and thereby cause corresponding movement of the other of said contact members in response to the inherent biasing force thereof, said stop member being so positioned as to be engaged by said other contact member following a certain amount of flexing movement thereof consequent

upon the operation of said operating means to flex said one contact member in opposition to the inherent biasing force thereof, separation of said contact member being effected in response to flexing movement of said one contact member an amount greater than that required to effect engagement of said other contact member with said stop member, a rigid current-carrying member supported by said base, a variable resistance spring transducer having one end physically and electrically connected to said rigid current-carrying member and having the other end physically and electrically connected to said other contact member, the inherent biasing force of said other contact member being such as to stretch said transducer from a contracted position to an expanded position an amount corresponding to the amount of movement of said other contact member in its traverse to the point of engagement with said stop member, said 20

transducer having a greater resistance in its expanded condition than in its contracted condition thereby to effect reduction of normal current to a lower value prior to interruption by separation of said contact members.
